UNITED STATES PATENT OFFICE

ROY W. SCHWEIKER, OF LANSDALE, PENNSYLVANIA, invented
CANOPY FOR LIGHTING FIXTURES

Application filed February 21, 1929. Serial No. 341,725.

Heretofore, the common practice of mounting the electric lamp socket in a porcelain or china side wall or ceiling lighting fixture has been to enclose or house the socket in a porcelain cover or a brass shell with an insulating lining to protect the screw threaded shell and the terminals against short circuiting. This practice has necessitated extra expense for the protective cover.

10 The common practice heretofore has been to provide special locking means to keep the electric lamp socket from turning or becoming loose within the canopy.

15 My invention has for its objects, first, the provision of a porcelain or china canopy for a lighting fixture having an integral internal housing which receives and surrounds the porcelain base of the electric lamp socket, thus preventing accidental short circuiting. 20 contact with the screws and terminals carried by said socket and obviating the necessity for providing a special protective cover or shell such as heretofore used for that purpose; second, to provide on the canopy an integral internal housing which receives and surrounds the porcelain base of the electric lamp socket and has means co-operating with the wall of said housing for preventing the turning of the socket and its base in the 25 canopy; third, to provide means on the canopy to co-operate with the guide for the pull chain of the socket, if the socket is of the pull chain type, which will prevent turning of the socket in the canopy.

30 35 Unlike earlier constructions where the electric lamp socket has merely been contained within the canopy, there is provided according to one part of my present invention, an internal housing on the interior of the canopy formed and arranged to surround the base of the lamp socket so that no metal part of the electric lamp socket is exposed and any possibility of short circuits within the canopy is obviated.

40 45 In respect to the improved means for preventing the electric lamp socket from turning in the canopy, the invention makes provision for the easy fitting together or assembly of the parts and entirely does away 50 with special fastenings for that purpose.

Those embodiments of the invention which are set forth hereinafter and are shown in the accompanying drawings relate both to key and to keyless fixtures, that is, to those which are operated by a pull chain or cord and those which are operated by a wall or other switch but as other embodiments of the invention are feasible, it is to be understood that the disclosure of special forms is by way of illustration, and not in limitation of the invention.

In the accompanying drawings: Figure 1, is a top plan view showing one embodiment of the invention;

Fig. 2, is a vertical section on the line 2—2, Fig. 1;

Fig. 3, is a detail side view of the lamp socket;

Fig. 4, is a view like Fig. 1, of another canopy and a modified lamp socket; and

Fig. 5, is a view like Fig. 2 on the line 5—5, Fig. 4.

In Figs. 1, 2, and 3, disclosure is made of an embodiment of the invention such as is adapted for use on a ceiling lighting fixture where the switch is located on the wall or at a point distant from the fixture.

The embodiment illustrated in Figs. 4 and 5 is that of a canopy where the lamp socket has a switch which may be operated by a pull chain or cord.

Referring first to Figs. 1, 2, 3, the canopy 1 is shown as an integral porcelain fixture having an enlarged upper part, a constricted central part, and a flared lower part which serves as a shade holder. The upper part is provided with the metallic strap 2 secured to the canopy by screws 3, said strap serving to connect the canopy to the outlet box. No claim is laid herein to the particular manner in which the ends of the strap 2 are seated in the seats 4, as this construction is set forth and claimed in my application Serial No. 337,638.

As commonly made, the usual canopy is merely adapted to contain the screw threaded metallic socket, said socket being received within the hollow back of the canopy. This necessitates the provision of a protective cover or shell carried by the lamp socket for the

purpose of preventing short circuits on the terminals and what would otherwise be exposed parts of the lamp socket.

The addition of this housing or protective shell makes the lamp socket more expensive and as many of the fixtures of this general type are highly competitive, it is desirable to minimize expense of manufacture.

In carrying out the invention in the embodiment shown in Figs. 1 to 3, the canopy 1 is provided with a chamber or concavity 5 located inside the canopy and formed by thickening or elongating the integral neck of the canopy in its central part as at 6 in the general direction of the longitudinal axis of the canopy. The chamber or concavity is provided with a bottom or seat 7 and there is an annular shoulder 8 pierced by an opening 9 which accommodates the screw threaded shell 10 of the lamp socket.

The lamp socket comprises the shell 10 and a body or base 11 of porcelain or insulating material, said shell being connected by screws 13 whose heads are shown exposed in Fig. 1 but which are, in practice, covered with a sealing material, as is the common practice in sockets. The terminal screws for the socket appear at 14, said screws being connected to the metallic pieces which constitute terminals of the socket. There is a transverse groove 15 in the insulating body 11 for the addition of the wires which are to be fastened to the terminal screws 14.

The insulating body 11 has wings or lugs 16 and the concavity 5 is provided with grooves 17 adapted to receive said wings or lugs, the purpose being to prevent the body 11 and the shell 10 carried thereby, from turning within the concavity 5 and the opening 8. The entire body 11 with its fittings is wholly contained within the concavity 5 and surrounded and housed thereby and has its upper surface preferably at the level of, or below, the upper end of the neck 6 so that the body will be properly protected.

The lamp socket is held in position by a porcelain or insulating nut 18 which is internally screw threaded and is screwed onto the screw threaded shell 10. The shade holding part 19 of the canopy which is integral with the central part 6 and upper part of said canopy flares outwardly below said central part is countersunk at 20 for the reception of the nut 18, the head of the nut overlapping the bottom of said shade holder and there being provided, by preference, a suitable gasket or washer 21 against which the head of the nut may screw and which is interposed between said head and the bottom of the shade holder. This arrangement permits a tight, non-rattling, joint, holds the insulating body 11 drawn against the bottom of the concavity 5, and otherwise provides a screw connection which can be readily loosened when desired.

The housing 6 which has the concavity 5 may also be provided in the same canopy having the channels 17, with an enlarged offset 22 from which leads a perforation through the neck 6, the purpose being to adapt the canopy for the use therewith of a lamp socket of the type having a switch if such be desired, as disclosed in Figs. 4 and 5. The canopy being provided with channels or notches 17 and the offset cavity 22, the fixture may be used either as one controlled by a wall switch or one having its own switch. According to whether the lamp socket has, or has not a switch, the form of the body 11 will be changed.

In Figs. 4 and 5, there is shown an embodiment of the invention wherein the lamp socket is provided with a switch of the pull-chain type and, to show the possibility of modification of the canopy without changing the essential principle of the invention, I have shown in Figs. 4 and 5 a canopy of the shadeless type.

The canopy 1 is provided with the attaching strap 2 which is secured by screws 3 and may be seated as at 4. The canopy has a cavity or chamber 5 in its neck 6, said cavity being of a depth suitable to accommodate or house the lamp-socket insulating-body 23.

Suitably connected to the body 23 is a screw threaded metallic shell 24 which receives the lamp. The shell 24 projects through an opening 9 in the canopy, the shoulder 8 being provided as in Figs. 1 and 2.

There is an outer shadelike porcelain finishing piece 25 which serves the purpose of a nut, having internally screw threads engaged with the shell 24. The member 25 is received in a counter-sink 20 in the canopy 1 and there is provided a suitable gasket 21 to permit suitable tightening without danger of breakage and to do away with looseness.

The walls of the cavity 5 are provided with channels 17 and an offset cavity 22 such as previously described. The terminals of the socket appear at 14, the body 26 of the socket being provided with grooves 27 in its side for the accommodation of the wires 28.

As with the construction in Figs. 1 and 2, so in the construction in Figs. 4 and 5, the terminals are housed and protected by the walls of the cavity 5 against accidental contact.

The socket being provided with the bell or mouth 28 through which the pull chain 29 passes, this bell or mouth is received within the supplemental cavity 22, rendering it unnecessary to provide on the body 26 the lugs or wings 16 used on the socket shown in Figs. 1 and 2, that is, the part 28 prevents the lamp socket from turning in the cavity 5, but it will be observed that as the channels 17 are provided in this form of fixture, the fixture of Figs. 4 and 5, like the fixture of 1 and 2, is adapted to accommodate the socket such as

shown in Figs. 1 and 2, as well as the one which is illustrated in Figs. 4, 5.

In both forms of the invention and in any modification thereof, the canopy is provided with an internal cavity formed in the neck of the canopy itself, adapted to house, surround, and protect that part of the lamp socket which carries the terminals, thus doing away with the usual protective shell carried by lamp sockets and eliminating the expense thereof.

What I claim is:

1. A canopy for a lighting fixture, embodying a body of insulating material having an enlarged hollow back or rear part, an enlarged front or outer part, a constricted central part located between the aforesaid rear and outer part, said central part being provided with an internal chamber or cavity having a recess in one of its walls and disposed outwardly in relation to the enlarged hollow back part aforesaid, and having a ring-shaped bottom, in combination with a lamp socket having an insulating base received within, and housed by, said chamber or cavity and provided with a projecting part received in said recess, and a screw threaded metallic shell carried by said body, said shell projecting through the ring-shaped bottom into the enlarged outer part aforesaid.

2. A canopy for a lighting fixture, embodying a body of insulating material having an enlarged hollow back or rear part, an enlarged front or outer part, a constricted central part located between the aforesaid rear and outer part, said central part being provided with an internal chamber or cavity having a recess in one of its walls and disposed outwardly in relation to the enlarged hollow back part aforesaid, and having a ring-shaped bottom, in combination with a lamp socket having an insulating base received within, and housed by, said chamber or cavity and provided with a pull-chain-bell received in said recess, and a screw threaded metallic shell carried by said body, said shell projecting through the ring-shaped bottom into the enlarged outer part aforesaid.

In testimony whereof I affix my signature.

ROY W. SCHWEIKER.
